(57) **CLAIM**

The ornamental design for a reclining chair, substantially as shown and described.

DESCRIPTION

FIG. 1 is an upper left front perspective view of a reclining chair in an upright position of my new design, wherein the supporting structure is shown in dashed lines, and is not part of the claimed design;

FIG. 2 is a front elevational view thereof;

FIG. 3 is a right side elevational view thereof, the left side is a mirror image;

FIG. 4 is a rear elevational view thereof; and,

FIG. 5 is a bottom plan view thereof.

The broken lines showing the reclining hardware in FIGS. 1–5 are for illustrative purpose only and form no part of the claimed design.

1 Claim, 3 Drawing Sheets**FIG. 1**

FIG. 5

FIG. 4
